UNITED STATES PATENT OFFICE

CHARLES MILLER, OF LONG ISLAND CITY, NEW YORK

DESIGN FOR A SHOE

Application filed March 26, 1931. Serial No. 39,243. Term of patent 3½ years.

To all whom it may concern:

Be it known that I, CHARLES MILLER, a citizen of the United States, and a resident of the city of Long Island, county of Queens, and State of New York, have invented a new, original, and ornamental Design for a Shoe, of which the following is a specification, reference being had to the accompanying drawing, forming part thereof.

The figure is a front perspective view of a shoe showing my new design.

The dominant feature of my design resides in the symmetrical arrangement of the openings shown in the counter and toe portions of the shoe.

I claim:

The ornamental design for a shoe, as shown and described.

CHARLES MILLER.
